FIG. 1

INVENTOR
Theodore Bodde
BY Francis J. Chamberlain
his ATTORNEY

UNITED STATES PATENT OFFICE.

THEODORE BODDE, OF NORTHFIELD, VERMONT.

STEAM-TURBINE.

1,033,868.

Specification of Letters Patent. Patented July 30, 1912.

Application filed December 20, 1911. Serial No. 666,887.

To all whom it may concern:

Be it known that I, THEODORE BODDE, a subject of the Queen of the Netherlands, residing in Northfield, county of Washington, 5 in the State of Vermont, have invented a certain new and useful Improvement in Steam-Turbines, of which the following is a true and exact description, reference being had to the accompanying drawings, which 10 form a part thereof.

My present invention relates to steam turbines and consists in part in a novel and effective arrangement for magnetically supporting a turbine element rotating about a 15 vertical axis, and in part in a novel modification of a turbine of the reaction wheel type especially adapted for laboratory demonstrations.

The various features of novelty which 20 characterize my invention are pointed out with particularity in the claims annexed to and forming a part of this specification. For a better understanding of the invention, however, and the advantages possessed by 25 it reference should be had to the accompanying drawings and descriptive matter in which I have illustrated and described forms of apparatus embodying my invention.

30 Of the drawings, Figure 1 is an elevation of one form of turbine embodying my present invention. Fig. 2 is a plan view of a portion of the apparatus shown in Fig. 1. Fig. 3 is an elevation of a modification, and 35 Fig. 4 is an elevation on a larger scale than Fig. 1 of a portion of the apparatus there shown.

In the drawings and referring first to the construction shown in Figs. 2 and 4, B, represents a base member to which the legs of 40 an arch-shaped permanent magnet A is connected. The magnet A is so magnetized that one of the poles of the magnet is at the center of the arch while the bottom ends of 45 the two legs of the magnet are each of the same polarity as the other and opposite in polarity to the center of the arch. The magnet A is formed at the top of the arch with an aperture A' terminating at its upper end 50 in a spherical seat A² for a ball G. The ball G is connected to and supports the pole-piece member F. The member F and advantageously also the ball G and the connecting neck are formed of magnetic mate-

rial and form in effect a polar extension of 55 the magnet A. Advantageously as shown the member F is in the form of an inverted cone having a rounded lower end F'.

The rotating turbine element is of the type 60 of Hero's reaction wheel, and comprises a tubular member or barrel D advantageously formed of copper or brass, and closed at its upper end by a cap member E of magnetic material. The latter is advantageously made of conical shape with its point E' 65 rounded like the member F. The barrel D is partially filled with water and has orifice arms formed by the ends of a tube I passing diametrically through the barrel D adjacent the upper end of the latter, to which it is 70 rigidly secured as by brazing. The tube I is provided with an orifice I' at its center and is provided at each end with an orifice I² opening horizontally at right angles to the tube, and the two orifices I² pointing in 75 opposite directions. The magnet A is made of such strength and the parts are so proportioned that the magnetic attraction between the polar portion F and the magnetic body E, which forms in effect an armature 80 for the magnet A, is sufficient to sustain the weight of the body E and barrel D and tube I.

When steam is generated within the barrel 85 D as by the heat of a burner, such as an alcohol lamp Z, placed on the base B, the steam discharged through the ports I² will set the barrel D into rotation. Since the pressure between the polar portion F and the magnetic body E is equal to the difference 90 between the magnetic attractive force acting between these bodies and the weight of body E, barrel D and tube I, the frictional resistance to the rotative movement 95 may be made very slight and with the simple apparatus shown it is possible to obtain high rotative velocities.

The ball and socket supporting connection for the pole-piece F gives the latter and the armature E a capacity for relative adjustment which I have found to be practically essential to the operation of the turbine at high speeds. If the pole-piece F be held rigid and the armature E be rigidly connected to the rotating turbine element any 100 slight lateral displacement of the armature with respect to the pole-piece results in causing the turbine element to break the 105

- magnetic suspension when rotated at high speed. When the pole-piece and armature are given the capacity for relative adjustment referred to, however, the rotating turbine element has a self centering capacity.
- 5 In such case on any slight lateral displacement of the points of contact of the pole piece and armature the former tends to rock into the position in which the point of contact is in line with the rotating axis of the
- 10 turbine element and the continued rotation of the latter tends to bring the parts back to the position in which the axes of the pole piece and armature member coincide. The
- 15 rounded contact surfaces F' and E' obviously contribute to this self-centering capacity.
- It is not essential, of course, that the pole-piece F from which the rotating element is suspended be energized by a permanent magnet, nor is it essential that the pole-piece be adjustably mounted in order to give the desired self-centering capacity. The latter may be obtained by making the
- 20 armature member adjustable with respect to the rotating turbine element, and in Fig. 3 I have shown a construction in which the pole-piece from which the turbine element is magnetically suspended is rigidly secured
- 25 in place, and forms a part of an electromagnet, and in which the armature coöperating with the pole-piece is non-rigidly connected to the rotating turbine element, although it will be understood that these two
- 30 features are not necessarily employed together. In Fig. 3, the permanent magnet A of Fig. 1 is replaced by an arc-shaped support AA to the top of which is secured an electro-magnet J provided with a pole-piece J' which differs from the pole piece F of Fig. 1 mainly in the fact that it is rigidly connected to its support. The armature element EA of Fig. 3 is of conical shape like the armature E of Fig. 1, but
- 35 unlike the latter is not rigidly connected to the barrel D of the turbine element. In this construction the upper end of the barrel D is closed by a cap member DA and the members EA and DA are connected by
- 40 a flexible wire or other filamentary member K which causes the armature EA to rotate with the turbine element, but permits the turbine element to rotate about its own axis and at the same time permits the armature
- 45 element EA to adjust itself with respect to the fixed pole-piece J' just as the adjustable pole-piece F of Fig. 1 is free to rock with respect to the armature element E of that figure.
- 50 The apparatus shown forms a very simple but effective and useful device for laboratory demonstrations; the use for which it was primarily devised. It will be apparent to those skilled in the art, however, that
- 55 some of the principles of construction em-

bodied in the present invention are capable of use in apparatus of a size and character adapted for ordinary commercial purposes.

While in accordance with the provisions of the statutes I have illustrated and described the best forms of my invention now known to me, it will be apparent to those skilled in the art that changes may be made in the form of the apparatus disclosed without departing from the spirit of my invention, and that under some conditions, certain features of my invention may be used with advantage without a corresponding use of other features.

Having now described my invention what I claim as new and desire to secure by Letters Patent is:

1. The combination with a steam turbine element rotating about a vertical axis and having a magnetic body secured to its upper end, of a magnet having a polar portion against which said body is held by the magnetic attraction between said body and said polar portion.

2. The combination with a steam turbine element rotating about a vertical axis and having a magnetic body of conical form and with—rounded apex secured to its upper end, of a magnet having a polar portion in the form of an inverted cone with a rounded apex, said body being held against said polar portion by the magnetic attraction between them.

3. The combination with a steam turbine element rotating about a vertical axis and having a magnetic body secured to its upper end, of a magnet secured thereto, a polar body, said first mentioned body being held against said polar body by the magnetic attraction between them, and one of said bodies being adjustable with respect to the part to which it is secured to give said bodies a capacity for relative adjustment whereby the turbine element is given a self-centering capacity.

4. The combination with a steam turbine element rotating about a vertical axis and having a magnetic body of conical form and with a rounded apex secured to its upper end, of a magnet having secured thereto a polar body in the form of an inverted cone with a rounded apex, said first mentioned body being held against said polar body by the magnetic attraction between them, and one of said bodies being adjustable with respect to the part to which it is secured to give said bodies a capacity for relative adjustment whereby the turbine element is given a self-centering capacity.

5. The combination of a magnet having a polar portion, a Hero reaction wheel provided with a magnetic body at its upper end which is held against said polar portion by the magnetic attraction between the latter and said body.

6. The combination of a stand, a magnet supported thereby and having a polar portion located above said stand, a Hero reaction wheel provided with a magnetic body at its upper end which is held against said polar portion by the magnetic attraction between the latter and said body, said reaction wheel being separated from said base a distance sufficient to permit of the interpolation of a burner for heating the reaction wheel.
